United States Patent Office.

CALVIN H. PAYNE, OF PROVIDENCE, RHODE ISLAND, ASSIGNOR TO HIMSELF AND WILLIAM E. BARRATT AND COMPANY, OF SAME PLACE.

Letters Patent No. 87,358, dated March 2, 1869.

IMPROVED CARRIAGE-JACK

The Schedule referred to in these Letters Patent and making part of the same.

To all persons to whom these presents may come:

Be it known that I, CALVIN H. PAYNE, of the city and county of Providence, and State of Rhode Island, have invented an Improved Carriage-Jack; and I do hereby declare the same to be fully described in the following specification, and represented in the accompanying drawings, of which—

Figure 1 denotes a side elevation,
Figure 2, a front-edge elevation, and
Figure 3, a vertical section of it.

In such drawings—

A denotes a standard or flat post, erected on a base-board, B.

Against the front face of this post is a flat bar, C, having its upper end scarfed, and provided with a series of right-angular notches, a a a. There is also in the front edge of the bar C, a series of holes or mortises, b b b, &c., for reception of a pin, c, connected with the bar by a chain, D.

The bar C is held in connection with the standard A by means of screws or bolts e e, which screw into the bar, and go through slots f f, formed vertically in the standard, the same being in order to allow of the bar being moved vertically relatively to the standard.

Within the lower part of the inner face of the standard A, is a chamber, or recess, g, which, formed as represented in fig. 3, is intended to receive a toggle, D, which, at its lower part, is fastened to the standard, as shown at h.

The toggle, at its upper part, is pivoted or jointed by a pin, m, to one angle of one end of a metallic lever-plate, E, formed as represented. This plate extends into a chamber, or recess, i, formed in the inner face of the bar C, in manner as shown in Figures 4 and 5, one of which is a rear-edge view, and the other, an inner-side view of the said bar.

At the other corner of its front end, the metallic lever-plate E is pivoted to the bar C, the connecting-pin being shown at k.

Furthermore, to the plate E, a lever, or handle, F, is affixed, it being arranged with the plate in manner as represented.

The lever-screw e constitutes a stop for the lever-plate E, which, when depressed, brings up against the said screw, in which case, the three joint-pins, h, m, and k, will be in or about in a straight line with each other, or the middle one be thrown a little forward, and in advance of the others.

When the bar C is at its lowest position, the handle F will be raised up into or nearly into a vertical position. Under these circumstances, by laying hold and depressing the handle, the plate E and toggle will be made to operate as toggles, to elevate the bar C.

In using the jack, the pin c, or some one of the notches a a a, when the lever is in its highest position, should be placed underneath the axle of a car-

riage to be raised. This having been done, it is only necessary to depress the handle F, in order to cause the bar B to rise and elevate the axle, so as to raise the wheel off the ground.

My present carriage-jack resembles, in some respects, that described in Letters Patent, No. 73,992, dated February 4, 1868, and granted to myself, and George S. Thompson, as assignees of myself the inventor; but in my present jack, the toggle is arranged directly between the standard and the movable bar, and in a chamber made in the standard, and thereby is better protected from injury.

That part of the lever-plate E, which constitutes the second toggle, is also arranged directly between and covered on opposite sides, by the standard and bar.

The new arrangement of parts makes a much better jack, both for use and durability.

I am aware of the carriage-jack which constitutes the subject of the patent, No. 38,936, granted, June 23, 1863, to Nathan Bagley. This jack, although in some respects analogous to mine, differs from it in several particulars. In the first place, it has two posts or standards, between which the movable or lifter-bar and the operating-lever and toggle are arranged, whereas, in my jack, I have but one standard, A, the movable or lifter-bar C being arranged directly against one side of such standard, and the chambers i and g are formed within the bar and standard, one chamber being in the bar, and the other in the standard. No such arrangement of a single standard, lifter-bar, and chambers, is shown in Bagley's carriage-jack. In my jack, the toggle D and the lever E are arranged between the standard A and the lifter-bar C, but such is not the case in Bagley's jack, in which the lever and toggle are arranged underneath the lifter-bar, and between the two standards. Thus, with my improvement, I dispense with one standard, and thus am enabled not only to cheapen the construction of the jack, but to make it thinner, lighter, and easier to handle.

I therefore claim, as my invention, my improved jack, made as described, that is, with its toggle D and lever E arranged between, and so as to be covered by the standard A and the movable bar C, and to operate in chambers or recesses g i, arranged in the standard and bar, in manner substantially as specified.

I also claim the arrangement of the lower connection e, of the standard A, and the movable bar C, with the toggle D and the lever E, so as to constitute a stop, to arrest the latter, when in its lowest position, as described.

CALVIN H. PAYNE.
